E. C. COVERT,
APPARATUS FOR FEEDING PULVERIZED FUEL,
APPLICATION FILED APR. 23, 1917.

1,365,662.

Patented Jan. 18, 1921.

UNITED STATES PATENT OFFICE.

EDSON C. COVERT, OF NEW KENSINGTON, PENNSYLVANIA, ASSIGNOR TO HEYL & PATTERSON, INC., OF PITTSBURGH, PENNSYLVANIA, A CORPORATION OF PENNSYLVANIA.

APPARATUS FOR FEEDING PULVERIZED FUEL.

1,365,662.

Specification of Letters Patent. Patented Jan. 18, 1921.

Application filed April 23, 1917. Serial No. 163,932.

To all whom it may concern:

Be it known that I, EDSON C. COVERT, a citizen of the United States, and resident of New Kensington, in the county of Allegheny

and State of Pennsylvania, have invented a new and useful Improvement in Apparatus for Feeding Pulverized Fuel; and I do hereby declare the following to be a full, clear, and exact description thereof.

10 My invention relates to apparatus for feeding pulverized fuel to a plurality of burners or furnaces.

The object of my invention is to provide a simple and reliable means for distributing the fuel to a plurality of fuel consuming devices; to return part of the fuel and air to the blower; and also to furnish an efficient means for automatically supplying the necessary air and fuel to make up for air and fuel that is being burned.

15 In the accompanying drawing, I have illustrated my invention, certain parts being broken away for purposes of clearness.

The numeral 2 designates a suitable hopper or receptacle for the pulverized fuel with the tapering bottom 3. An injector 4 enters the lower end of the hopper 2, the outlet of said injector being separated slightly from the lower end of the pipe 5, whereby a small stream of coal and air is forced up through said pipe and discharged against the concaved cone 6 which acts as a spreader. This cone 6 forms part of the cage 7 contained within the chamber 8 above the hopper 2.

20 This cage 7 has the openings 9 which are regulated by the valve or ring 10 connected by the rod 11 to the lever 12 which at its other end is connected to a diaphragm 13 mounted on and in operative connection with suction pipe 14 communicating with the cage 7 and at its opposite end with the fan or blower 15. A pipe 16 leads from the blower to the furnaces 16^a to be supplied with fuel and said pipe is tapped at intervals by the pipes 17 leading to the burners 18. Valves 19 are provided to control the supply to the furnaces.

25 The pipe 16 is connected up to the return pipe 20 which communicates with the blower. This return pipe has the section 20^a of smaller diameter than pipe 16 so that the fuel supply in the circuit is always under pressure. That part of the fuel passing back to blower through return pipe of fuel cir-

cuit is again forced around the circuit with fresh fuel and air drawn by fan suction through mixing chambers on hopper of fuel supply.

In operation the pulverulent fuel in the 60 hopper is driven up the pipe 5 against the cone-deflector 6. The suction pipe 14 terminates in the cage with variable openings controlled automatically by the diaphragm 13, so that regardless of the amount of air that 65 is passing through the cage to blower, its velocity at the cage openings will be the same, and it will pick up the same amount of fuel per cubic foot of air passing to the blower.

70 A slight demand for additional air and fuel will form a slight vacuum on suction pipe and cause diaphragm to move downward, thereby causing opposite end of lever 12 to move upward and also the valve 10 to 75 enlarge the openings 9.

By my invention the fuel is fed automatically and its feed depends on the ability of air at a given velocity to carry fuel of a certain richness. With all the burning devices 80 shut off the blower would continue to circulate the fuel contained in the system over and over again.

What I claim is:

1. In apparatus for feeding pulverulent 85 fuel, the combination of a fuel-supply, a blower, a suction-pipe connecting said blower with said fuel-supply, a continuous pipe circuit connected to the intake and discharge of said blower, the return pipe of said circuit having a portion of smaller diameter than the outgoing pipe adjacent to said blower, and branch pipes leading from said outgoing pipe.

90 2. In apparatus for feeding pulverulent 95 fuel, the combination of a fuel supply, a blower, a suction pipe, means for supplying fuel and air to said suction pipe, means controlled by the pressure in said suction pipe for varying the size of said intake opening 100 to said pipe, a continuous pipe circuit connected to the intake and discharge of said blower and branch pipes leading from said pipe circuit to the point of consumption.

3. In apparatus for feeding pulverulent 105 fuel, the combination of a fuel reservoir, an injector, a pipe in said reservoir in line with said injector, a cage whose bottom forms a spreader for the air and fuel, a valve controlling the openings of said cage, a blower, 110

a suction pipe communicating with said cage and said blower, means controlled by the partial vacuum formed in said suction pipe, for moving said valve, and a pipe leading 5 from said blower to the point of consumption.

4. In apparatus for feeding pulverulent fuel, the combination of a fuel reservoir, a blower, a suction pipe, a discharge pipe, and 10 branches leading therefrom, said discharge pipe being in the form of a loop with its discharge end connected to said suction pipe, and automatic means for varying the said opening between said fuel reservoir and said 15 suction pipe by the pressure in said suction pipe.

5. In apparatus for feeding pulverized fuel, the combination of a fuel reservoir, a blower, a suction pipe connecting said blower 20 with said reservoir, a continuous pipe circuit connected to the intake and discharge of said blower, means for producing a dust

cloud of fuel suspended in air in said fuel reservoir, and means for automatically varying the size of the opening between said fuel 25 reservoir and said suction pipe.

6. In apparatus for feeding pulverized fuel, a combination of a fuel supply, a blower and suction pipe, a continuous pipe circuit connected to the intake and discharge 30 of said blower, branch pipes leading from said pipe circuit to the point of consumption, and a valve for regulating the supply of fuel and air to said suction pipe, the said valve being controlled by the pressure in said 35 suction pipe for maintaining a constant velocity of the air through the opening to said suction pipe.

In testimony whereof, I the said EDSON C. COVERT, have hereunto set my hand.

EDSON C. COVERT.
